ATTORNEY.

UNITED STATES PATENT OFFICE.

JAMES C. PAGE, OF AKRON, KANSAS.

TERRET.

SPECIFICATION forming part of Letters Patent No. 488,249, dated December 20, 1892.

Application filed December 15, 1890. Renewed August 26, 1892. Serial No. 444,152. (No model.)

To all whom it may concern:

Be it known that I, JAMES C. PAGE, a citizen of the United States, residing at Akron, in the county of Cowley and State of Kansas, have invented certain new and useful Improvements in Terrets or Hame-Rings for Guiding Horses; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to harness terrets or hame-rings for guiding the reins of the harness and which may be attached to the hame, saddle or other suitable or convenient part of the harness.

20 My invention has for its object to so construct a terret that the reins shall be guided thereby so as to occupy at all times a substantially horizontal position and counteract all tendency to twisting the same and to keep 25 the rein buckle outward and away from the body of the horse and prevent its becoming caught or entangled in any part of the harness or the usual fly-nets covering the horse.

For this purpose my invention consists in 30 a terret which may be of the usual or any suitable form, provided with a narrow rectangular guiding slot approximately of the contour and size of the cross section of the rein and formed by two guiding rollers, one of 35 which is provided with circular flanges embracing the other and which rollers are preferably situated at the bottom of the loop or opening of the terret or hame ring. And my invention consists moreover in a terret provided with such guiding rollers one or both of 40 which may be made removable from the terret and retained by a spring-latch at the side of the terret-ring and bearing against the end of the spindle or spindles of the roller or 45 rollers. And my invention finally consists in such further details, combinations of parts and features as will be hereinafter pointed out and covered in the claims.

In the accompanying drawings:—Figure 1 50 represents a vertical central section of a terret embodying my invention; Fig. 2 a front

elevation of a portion of a hame with the said terret applied thereto; Figs. 3 and 4 side elevations of modified forms of terrets embodying the said invention, Fig. 4 being shown 55 partly in section.

Referring first to Figs. 1 and 2 it will be noted that the terret shown therein consists of the usual ring A provided with the ordinary screw-threaded shank, a, for screwing 60 the same into the hame. A rectangular slot through which the rein, shown in cross-section at C, passes is preferably formed by the two guiding rollers, D and E, the upper roller E, of which is preferably provided with the 65 guiding flanges or disks, e, e, which embrace the lower roller D at its ends in such a way that no space is left for the reins to slip out of the slot B or become caught. The inner faces of the disks, e, e, are preferably beveled 70 as shown, in order to prevent any direct friction against them when the draft on the lines is inclined to one or the other side. I preferably make one or both of the guide rollers 75 removable. This may be done in various ways, but I consider the one shown as the most desirable and effective. The rollers D and E it will be observed are mounted on the spindles, d' and e', respectively which spindles are removable and preferably provided at 80 their outer ends with squared heads, d², e², fitting into corresponding countersinks in the side of ring A. When in position they are held in place by the spring latch or keeper, F, pivoted at, f, in the side of the ring and of 85 sufficient extent to cover both the heads d², and e². In order to prevent this spring or keeper from being caught in the harness or otherwise deranged the same fits into a recess, a², in the side of the ring, so as to be flush 90 with the same.

The manner of operating and using this terret is obvious from the foregoing. When the reins are in place between the rollers they are always kept in a substantially horizontal position and prevented from twisting. The buckle is consequently always kept outward and prevented from becoming caught in the fly-net, or other portion of the harness. At 95 the same time the movement of the reins is permitted and facilitated by the anti-friction rollers D and E. The object of placing the

said rollers in the lower portion of the ring is to afford ample space in the ring above the same to "do up" the lines when unhitching.

When it is desired to remove the rollers 5 from the terret the spring-latch, F, is turned aside at right-angles to its ordinary position, when the spindles, d', e', may readily be withdrawn.

In Fig. 3 I show a somewhat modified form 10 of a terret involving my invention, which differs from the foregoing in the following particulars. In the place of the screw shank I have here provided the same with a depending and hooked lug, G, extending downward 15 at one side of the terret so that the same will occupy a substantially upright position when attached to the inclined sides of a hame. The mode of attaching the same is preferably by staples, g, g', riveted or otherwise secured to 20 the hame, g, and engaging at their tops the lug, G, and the lower portion of the terret, as shown.

Still another form of terret is shown in Fig.

4. There the means for securing the same to 25 the hame consists in a slot, H. The terret is in this instance secured to the hame by a strap secured thereto and passing through the slot H. In this modification I have shown

only one of the rollers removable, viz: the roller, D.

30

It is manifest that the devices shown to illustrate my invention may be modified in many particulars without departing from my invention. I do not therefore desire to be limited to the exact details shown and described, but

What I claim and desire to secure by Letters Patent is:

1. In a terret the combination with a terret-ring and a guiding-roller of a removable spindle upon which the guiding-roller turns and a spring-latch at the side of the terret-ring for keeping the said spindle in position, substantially as described.

40

2. A terret provided with a guiding-slot for 45 the reins and a depending lug extending downward at one side of the terret, whereby the terret may be attached in an upright position to the hame, substantially as set forth.

40

In testimony whereof I affix my signature in presence of two witnesses.

JAMES C. PAGE.
